Application September 28, 1934, Serial No. 745,860
In Germany October 3, 1933

8 Claims. (Cl. 235—6)

The present invention relates to bookkeeping or accounting machines and more particularly to that type used in savings banks for recording the customary deposits and withdrawals. The present invention is intended to diminish the amount of manipulation necessary in operating such machines. To this end the present invention includes structure which enables a movement of a balance lever to set up the mechanism for taking a proper algebraic total from the balance totalizer, and also to start the machine. The provision of this mechanism makes it unnecessary to press a motor bar after the lever is adjusted.

With this and incidental objects in view, the invention includes certain novel features of construction and combinations of parts, the essential elements of which are set forth in appended claims and a preferred form or embodiment of which is hereinafter described with reference to the drawings which accompany and form a part of this specification. In said drawings:

Fig. 1 is a diagrammatic view of the keyboard;

Fig. 2 is a side elevation showing the amount differential mechanism and totalizer assemblies;

Figs. 3 and 4 are side elevations of details of the balance totalizer;

Figs. 5 and 6 are side elevations of details of the overdraft mechanism;

Fig. 7 is a front sectional view showing details of the balance totalizer and its actuating mechanism together with parts of the overdraft mechanism;

Fig. 8 is a perspective view of the overdraft mechanism;

Fig. 9 is a front view of part of the machine broken away to show the connection between the transaction differential and the totalizers;

Fig. 10 is a plan view of parts shown in Fig. 9;

Fig. 11 is a front sectional view showing the connections from the keyboard to the balance totalizer for shifting the latter;

Fig. 12 is a side elevation of the balance lever and certain of the parts over which this lever exercises a control;

Fig. 13 is a side elevation of the transaction key bank and the balance lever together with parts connecting the two;

Fig. 14 is a side elevation of certain parts of the transaction key bank; and

Fig. 15 is a side elevation showing some of the connections between the keyboard and the balance totalizer.

GENERAL DESCRIPTION

The mechanism illustrated herein discloses a machine having one adding and subtracting or balance totalizer of the customary type embodying reversely rotated wheels. It also includes a row of interspersed adding totalizers to accumulate separately the deposits, withdrawals, positive old balances, negative old balances, positive new balances, and negative new balances, and two other rows of such totalizers for accumulating the various classifications of deposits and withdrawals.

When a patron presents his passbook for the purpose of making a deposit, the old balance is entered in the balance totalizer, as well as in one of the special totalizers assigned such old balance. The deposit is then entered in the balance totalizer and in its special totalizer. The new balance is then taken from the balance totalizer by a lowering of the balance lever from its "add" to its "balance" position. The lowering of this lever causes the proper one of two blind new balance keys to be depressed, which in turn causes the selection of one of two blind keys for selecting the proper side of the balance totalizer. Further movement of the lever causes the depression of the selected one of these latter blind keys and thereby positively moves a selecting rider for the balance totalizer to its proper position. The selection of these blind keys and the resulting shifting of the selecting rider for the balance totalizer is controlled by a suitable overdraft mechanism with the result that a proper algebraic total is taken. The very last portion of the movement of the balance lever causes the motor clutch to be released to start the machine.

Near the end of the operation of the machine the balance lever is automatically returned to its home position and the machine comes to rest.

DETAILED DESCRIPTION

Keyboard

45 The keyboard for the present machine is shown diagrammatically in Fig. 1 and includes amount keys 150, two rows of special totalizer keys 151 and a row of transaction keys bearing appropriate legends. In this transaction bank 50 the keys D and W represent deposits and withdrawals respectively and the keys POB and NOB represent positive old balances and negative old balances respectively. The two blind keys situated near the center of this bank represent the positive and negative new balances.

A key stem 24 is situated to the right of the transaction bank and cooperates with two blind keys 20 and 22 used to shift the operating mechanism for the balance totalizer so that amounts may be entered thereon algebraically. A kind of operation lever 141 is provided to take the totals from the various totalizers for the transaction bank and for the two banks of special totalizer keys. Three totalizer coupling levers 142 also are provided for use in taking totals in these banks. The function of these levers is to select a particular totalizer when it is desired that the total be taken therefrom. The present invention, however, is not involved with the details of the taking of totals from any of the totalizers in these three rows, so the operation of these levers is not given.

The special totalizer keys 151 in the two left-hand rows control only their respective totalizers, while the transaction keys in the right-hand row control not only the respective totalizer assigned to each, but further control the operation of the balance totalizer. It must be remembered that the kind of operation lever 141 is used in taking totals from the totalizers for the three rows of totalizer selecting keys but is not used when a total (new balance) is taken from the balance totalizer, for such operations are performed with the lever 141 in its "addition" position.

For taking totals from the balance totalizer, a balance lever 149 is provided. When this lever is moved to its balance position it depresses the key stem 24 and with it one of the blind keys 20 or 22 to shift the balance totalizer. Movement of this lever to its balance position also otherwise completely conditions the machine for a balance operation and starts the operation without any further manipulation of the keyboard.

During itemizing operations the machine is started when any one of the four keys in the transaction bank is depressed, these keys in the present machine being constructed as motor keys.

Differential mechanism

The differential mechanism is shown in a general way in Figs. 2 and 9, Fig. 2 showing the amount differential and Fig. 9 a few parts of the transaction differential. Referring to Fig. 2, the differential includes two complementarily movable arms 143 and 144 brought together through the action of complementary gears to adjust a minimum movement segment 145 under the inner end of a depressed amount key 150. These parts are actuated by a suitable pinion secured to a shaft 146 oscillated during each operation of the machine. The detailed movement of these parts is not given, since it is fully shown and described in the United States Patent No. 1,792,569 issued to Ernst Breitling on February 17, 1931. It might be noted, however, that the particular form of planet gearing shown in Fig. 2 is not present in the patent but is shown in a later patent disclosing the mechanism for taking totals in this type of machine. This later patent is numbered 1,899,455, issued to Ernst Breitling on February 28, 1933. For an understanding of the present case it is sufficient to say that the movement of the complementarily movable members 143 and 144 causes a movement of a large gear 157 to an extent commensurate with the value of the depressed amount key 150. The positioning of the minimum movement segment 145 causes a positioning of its corresponding amount type wheel

through a train of gears 147, 148, 152, 154, 155, and 156 and a rack 157', the gear 147 being driven by the segment 145 through beveled teeth appearing on both members.

5 The differential mechanism for the transaction banks is partially shown in Fig. 9 and includes complementarily movable members 106 and 107 and a minimum movement segment 105. As is customary in the art, the differential mechanism for these banks controls the relative positioning of the various totalizers and the actuating mechanism, so that an amount set up on the keyboard will be entered in the appropriate totalizer under control of the totalizer selecting keys. 10 However, since the details of this differential mechanism are not necessary to an understanding of the present invention, they are not shown.

Totalizers

20 The machine on which the present invention is shown includes three rows of interspersed totalizers (Fig. 2) situated radially about a central shaft 146. For identification these rows are numbered I, II, and III. Each of these rows customarily contains nine totalizers. In the present instance two of the rows contain nine totalizers assigned to the two rows of special totalizer keys and the third row contains six totalizers assigned to the transaction keys. The construction of these interspersed totalizer units and the operation thereof are generally well known in the art and a form corresponding very closely to that used in the present mechanism is shown and described in U. S. Patent 1,898,933 issued to Bornkessel et al. on February 7, 1933. Details of 25 this mechanism, however, are not necessary to an understanding of the present invention, so they are not shown.

30 There is also provided a balance totalizer consisting of only one totalizer unit but having two reversely rotating wheels in each decimal order. This totalizer unit is numbered IV (Fig. 2) and is better shown in Figs. 3, 4, and 7. It includes two reversely actuated wheels 57 and 59 (Fig. 7), a pair of which is provided for each decimal order. The operation of these wheels is briefly as follows:

35 The differential rotation of large gear 157 (Figs. 2 and 3) commensurate with the value of the numeral key depressed in that particular decimal order is transmitted directly to pinion 158 (Fig. 3) and from there to pinion 59. Since at the time of this operation pinion 59 is engaged with pinion 159, the motion will be transmitted to the former and to sleeve 153 (Fig. 7) secured to this pinion. A rider 160 is loosely mounted on a shaft 130 and is slidable longitudinally of the sleeve 153, as clearly shown in this figure. The rider has an upwardly extending prong protruding through a longitudinal slot in the sleeve 153 and is adapted to be moved longitudinally into the plane of either of the totalizer wheels 57 or 59 by a longitudinal movement of shaft 130. When the rider is so moved it is in a position (see Fig. 4) to rotate one of the totalizer wheels 57 upon rotation of the pinion 59 and sleeve 153.

40 The reverse rotation of wheels 57 and 59 is made possible by the gear 51 on the shaft 130 (Fig. 4) and gears 52 and 54 (Fig. 7) connected by a sleeve 53. When a rotation is imparted to the wheel 59, the movement is transmitted through a sleeve 53 and a gear wheel 48 to the wheel 54, sleeve 53, gear 52, and then to gear 51. Rotation of the gear 51 causes rotation of a 45 gear 48 attached to a sleeve 55, on which the

totalizer wheel 57 is mounted. It will be noted that gear 51 is sufficiently broad to mesh with gear 52 and also with gear 48.

Each of the totalizer wheels 57 and 59 carries a tooth 139 (Fig. 4) sufficiently long to strike a finger 132 depending from an assembly of parts 133 appearing directly over the totalizer wheels in Figs. 4 and 7. A long tooth of an actuated totalizer wheel displaces the finger 132 whenever the long tooth 139 is moved through zero. This movement of the fingers 132 is for the purpose of transferring units from one order to another and is assisted in this action by discs 161 and 162 and the mutilated gears 136 and 137 appearing in Fig. 4. However, since the details of this mechanism are not necessary to an understanding of the present invention they are not given.

It will be noted, however, that the finger 132 (Fig. 7) cooperating with the totalizer wheels 57 and 59 of the highest decimal order is pinned to the shaft 134 so as to impart a slight rotation thereto whenever the wheels of highest order pass through zero.

Overdraft mechanism

The machine on which the present invention is shown includes a device commonly known as an automatic overdraft mechanism. This mechanism causes the totalizer to add a unit in the lowest decimal order whenever the totalizer wheel of highest order passes from zero to 9 or from 9 to zero to correct the inaccuracy appearing in totalizers of this type whenever they are carried through zero to a negative quantity or returned through zero to a positive quantity.

The mechanism also includes the additional feature of allowing this additional or fugitive unit to be added in the units order only when an actual overdraft occurs and not when the totalizer passes from 9 to zero by exceeding its capacity in a positive direction or by passing from zero to 9 after having been overdrafted during a previous operation.

This mechanism is illustrated in Figs. 5, 6, 7, and 8. Referring to Fig. 8, it is seen that whenever either of the totalizer wheels 57 or 59 in the highest decimal order passes through zero it strikes the finger 132 pinned to the shaft 134 and imparts to this shaft a counter-clockwise rotation. A sleeve member 163 is situated on the right-hand end of shaft 134 and is connected thereto by a pin and slot connection (see also Figs. 6 and 7). This allows the shaft 134 to be shifted axially without corresponding movement of sleeve 163 but causes the sleeve to receive whatever rotation is imparted to the shaft. This sleeve is connected to a gear 164 by a spring 165, the spring being secured to both of these parts, and sufficiently strong that a partial rotation of sleeve 163 will be imparted bodily to gear 164 if the latter is free to rotate. The gear 164 is loosely mounted on shaft 134 and has a shoulder 166 (Figs. 5 and 8) lying in the vertical plane of a shoulder 167 on the sleeve 163. These two shoulders normally lie some distance apart, as shown in these figures. With this construction, when the finger 132 (Fig. 8) is given a rotation by one of the totalizer wheels 57 or 59, a corresponding rotation is imparted to the sleeve 163 which, through spring 165, will rotate gear 164 if the same is not positively held against rotation. If it is so held, the spring 165 will be tensioned and upon passage of the long tooth 139 out of the path of the finger 132 the shaft 134 will spring

back to its original position, relieving the tension in the spring. A segment 168 (Figs. 5 and 8) is loosely mounted on a shaft 169 and carries a stud 172 having pivoted thereon a dog 173. A sleeve member 175 is also loosely mounted on shaft 169 and carries a four tooth restraining wheel 170, four radial teeth 176, and a mutilated gear 180. The four tooth restraining wheel 170 lies in the vertical plane of a dog 173, which dog is constantly held against the wheel by the tension of a spring 174 secured to the dog and to a projection on the left side of the segment. The four teeth 176 are disposed around the sleeve 175 equidistantly and lie in two different planes. As shown in Fig. 8, these teeth lie alternately in two planes. An arm 181 is secured to shaft 130 (Figs. 6 and 8) and lies in the plane of two of the teeth 176 when the balance totalizer is set for addition, and in the plane of the other two teeth when the totalizer is set for subtraction. The operation of these parts is briefly as follows:

When an overdraft appears in the register, the shaft 134 is rotated counter-clockwise, causing a counter-clockwise rotation of gear 164 and clockwise rotation of segment 168 as well as wheel 170, teeth 176, and gear 180 through the operation of dog 173 by the gear 168. If the sign of the balance in the balance totalizer is positive at the beginning of this operation, the arm 181 will be lying out of the plane of the tooth 176 situated closest to it at this time. Therefore the segment 168 will be free to rotate, upon rotation of shaft 134. This causes a rotation of the sleeve 182 (Fig. 7) as well as the transfer eccentric 183 to enter the fugitive unit in the lowest decimal order. The precise manner in which this unit is entered is not necessary to an understanding of the present invention and will therefore not be described.

Upon the return of shaft 134 to normal position, by parts of the transfer mechanism in the highest decimal order, the segment and dog 173 will return to their original position, the dog 173 ratcheting over one of the teeth 170 to allow the wheels 170 and 180 and teeth 176 to remain in their moved positions. This places one of the teeth 176 of the other plane in a position to have its movement restricted by the arm 181 unless the arm and shaft 130 are moved to their opposite lateral positions for the next operation involving passage of the highest wheel through zero.

During the normal operation of the machine, when the balance totalizer is in a positive condition and is overdrafted to a negative condition, the arm 181 will not prevent the entry of the fugitive unit. Likewise when the totalizer is in a negative condition and is returned through zero to its positive condition, the arm 181 will not prevent the entry of the fugitive unit, since the four teeth 176 are rotated 90 degrees by each overdraft passage of the totalizer through zero. Thus as long as the operation of the machine involves transactions causing the balance totalizer to pass through zero positively and negatively in alternate succession, the arm 181 will have no restraining action at any time, the totalizer being positioned alternately in its adding and subtracting positions during these operations involving the overdraft. However, should the totalizer have its capacity exceeded in either direction, the arm 181 will be effective to restrain the entry of the fugitive unit by lying in the path of a tooth 176 and thereby causing gear 164 to be held against rotation until the long tooth 139 passes

the finger 132 and the spring 165 rotates shaft 134 and finger 132 to normal position.

When taking a negative new balance from the totalizer, the adding wheels are left standing with a series of 9's thereon. This is because the subtracting wheels are turned to zero when taking a negative new balance. Therefore, when entering a positive old balance on the adding wheels immediately following the taking of a negative new balance, the highest order totalizer wheel will pass from 9 to zero, that is to say, the same as though the totalizer exceeded its capacity. This will trip the overdraft mechanism to add one into the units order to correct the balance therein. This result will be obtained because a shoulder 176 will not be in the path of the arm 181, and therefore 181 will not suppress the entry of the "fugitive one" in the totalizer. As pointed out above, the suppressing arm 181 is effective only when the sign of the total in the totalizer is not changed in the totalizer. When the total changes its sign to negative, a shoulder 176 is placed in the path of the arm 181. Subsequent taking of a negative total does not change this condition, but subsequent shifting of the totalizer rider to the positive side of the totalizer for entering the old balance shifts the arm 181 out of the path of the shoulder 176, so that when the highest order wheel passes from 9 to zero, one is added into the units order, and a correct old balance will result in the balance totalizer, even though the wheels were all standing with 9's thereon before the old balance is entered. The totalizer is also automatically corrected when entering a negative old balance following the taking of a positive new balance.

The operation of this overdraft mechanism is given only in a general way, since a very similar structure is fully shown and described in the above mentioned patent to Bornkessel et al. See particularly Figs. 16 to 21 of this patent.

Overdraft control of totalizer selection

Fig. 8 also discloses mechanism for causing the overdraft mechanism to automatically select either of two totalizer selecting keys for depression. The mechanism operates in such a manner that whenever the balance in the balance totalizer is positive, one of the two totalizer selecting keys is selected, and whenever the balance is negative, the other totalizer selecting key is selected. In the present instance the keys selected are the blind positive and negative new balance keys situated in the transaction bank and used to select either of the two new balance totalizers for separately accumulating positive and negative new balances. As above described, whenever the balance totalizer passes from positive to negative or vice versa, the gear 180 receives a 90 degree rotation. By means of the mutilated construction of this wheel 180 (Figs. 6 and 8) a 90 degree rotation thereof will cause a 60 degree rotation of a wheel 184 and a disc 185 connected thereto by sleeve 186, the parts 184 to 186 being loosely journaled on shaft 187. A triangular cam groove 188 is cut in the disc 185 and is so situated that it moves a roller 189 in one direction or the other during each 60 degree rotation. These movements of the roller 189, it will be observed, are alternate, so that each time the gear 184 is given a movement, the roller 189 will be moved in a direction opposite to its last movement. The roller 189 is situated on the upper end of a bell crank 190 connected by a link 191 to a lever 192 connected by a sleeve 193 to an arm 194 having

5 pivoted thereto a vertical link 195. It is now obvious that 60 degree rotations of gear 184 will move link 195 upward or downward depending upon its previous movement. The link 195 is 10 connected to a lever 196 (see also Fig. 13) pivoted on a stud 197 and connected to a detent slide 97. The lever 196, together with an arm 198, supports the detent slide 97 for movement in the key bank. Two sliding levers 98 and 99 are 15 pivoted to the slide 97 and are tensioned for outward movement by a spring 199 connected to each. These levers 98 and 99 have slots adapted to embrace studs 100 and 101 on the blind new balance keys and are restrained in their outward movement by the studs 100 and 101. Each of the levers 98 and 99 has a long prong adapted to cooperate with stud 96 (Fig. 13) on the upper arm of the bell crank 94 pivoted on the stud 95. Each lever also has a short prong adapted to contact studs 100 and 101 when the levers lie in a position where their long prongs cooperate with the stud 96. By this arrangement of parts it is evident that when the link 195 is in its upper position, the detent 97 will lie in its lower position, where 20 the long prong on lever 98 will contact stud 96 and the short prong will contact the stud 100, so that upon the clockwise rotation of the bell crank 94 the blind positive new balance key will be depressed and when the link 195 is moved to its 25 lower position by the balance totalizer being overdrafted, the slide 97 will be raised to its upper position where the long prong on the lever 99 will contact the stud 96 and the short prong will contact stud 101, so that upon clockwise moving 30 of the bell crank 94 the blind negative new balance key will be depressed.

Totalizer selection for interspersed adding totalizers

40 The various interspersed totalizers situated in rows I, II, and III (Fig. 2) are selected for operation by the three rows of totalizer selecting keys shown in Fig. 1, as is customary in key set machines of this general character. The differential mechanism situated in these key banks (Fig. 45 9) shifts mechanism in the totalizer assemblies, so that when the totalizer shafts are moved to engage the totalizers for actuation, the desired totalizer in each row will be coupled with the 50 actuating mechanism.

The segment 105 that is differentially positioned under the end of a depressed totalizer selecting key corresponds to the segment 47 in the above mentioned Breitling Patent 1,792,569 and is connected by a short sleeve 308 to a segment 299 meshing with a pinion 291 secured to a short sleeve 292. A segment 293 also is secured to the sleeve 292 and meshes with a pinion 294 secured to a drum 295 rotatably mounted on shaft 34. As shown in Fig. 9, this drum carries a helical 55 groove in its surface in which rests a roller 296 mounted on a bent arm 297 secured to a plate 300 by a sleeve 298. As better shown in Fig. 10, the plate 300 embraces restricted portions in shafts 130 and 305, so that movement of the plate 300 to the right or left will impart a corresponding movement to these shafts. Shaft 130 is grooved to accommodate riders 160, which connect the 60 actuating wheels 50 with the totalizer wheels 59, and shaft 305 carries a longitudinal groove 306 (see also Fig. 2) and notches 307, one for each decimal order, which constitute an aligning means, so that only the totalizer wheel aligned with rider 160 will be free to rotate with the 65 actuating wheel 50.

By the above mechanism, when the segment 105 is adjusted by operation of the differential mechanism as fully described in the Breitling Patent 1,792,569, the segments 290 and 293 are correspondingly adjusted and rotate drum 295. Such rotation adjusts plate 300 bodily to the right or left, causing a corresponding adjustment of the shafts 130 and 305. In this manner the various totalizers are adjusted under control of the depressed totalizer selecting keys.

Selection of the proper side of the balance totalizer for adding and taking the new balance

This mechanism is disclosed in Figs. 11 and 15. As heretofore mentioned, the six keys in the transaction bank control the selection of the positive and negative sides of the balance totalizer. This control is exercised through the provision of a detent slide 10 (Fig. 14) pivoted on two arms for movement in the key bank in the customary manner. This slide 10 has six cam portions, three of which cooperate with the deposit, positive new balance, and positive old balance keys to select the positive side of the balance totalizer, and three cams cooperating with the withdrawal, negative new balance, and negative old balance keys to select the subtracting side of the balance totalizer. The depression of any one of the first mentioned keys causes the slide 10 to be moved upward in the key bank, while depression of any one of the last mentioned keys causes the slide to be lowered. This raising or lowering causes a corresponding movement to be imparted to a link 11 pivoted to the slide 10 and to an arm 12 pivoted to the lower end of the link 11. This causes movement of a lever 13 (Fig. 12) connected to lever 12 by a sleeve 204, and movement of a link 14 connected to the lever 13, and further causes oscillation of a lever 15 connected to the link 14 and pivoted on a stud 203. Oscillation of the lever 15 causes an upward or downward movement of a slide 16 supported by the lever 15 and by an arm 202. Slide 16 has levers 17 and 18 pivoted thereon and pressed outwardly by the tension of a spring 205 connected to both. The levers 17 and 18 each have a long and a short prong, the long prongs being adapted to contact the underside of a stud 23 on the key stem 24, while the short prongs are adapted to contact studs 19 and 21 on blind keys 20 and 22 situated on either side of the key stem 24. It is apparent, from inspection of the drawings, that when slide 16 is moved to its upward position by depression of one of the three keys for selecting the positive side of the balance totalizer, the short prong on the lower lever 17 will engage stud 19 on the lower blind key 20 and the long prong will engage the stud 23 on the key stem 24. Likewise when any one of the three keys for selecting the subtracting side of the totalizer is depressed, the slide 16 will be lowered to the position shown in Fig. 12 and the upper lever 18 will contact the studs 21 and 23 for depressing the blind key 22. A slide 206 (Figs. 11 and 15) is suspended on arms 207 and 208 for the customary movement in its bank. This slide 206 has two cams 209 and 210 situated under studs 19 and 21 on the blind keys in this bank. From an inspection of Fig. 15 it can be seen that when the blind key 20 is depressed, stud 19 will engage cam 209 and lower the slide 206, whereas when blind key 22 is depressed, stud 21 strikes cam 210 and raises slide 206. A pawl 211 is pivoted at 212 and is held by a spring 213 in engagement with either of two notches in slide 206. This pawl is provided so

that this slide 206 will be held in either of its positions until positively moved to the other position by depression of one of the blind keys. A segment 214 is pivoted at 215 to the key bank and carries a stud 216 lying within a slot in the slide 206. A segment 217 meshes with the segment 214 and is secured to another segment 218 lying adjacent thereto. Segment 218 meshes with a pinion 219 secured to a gear 220. By this train of connections movement of slide 206 causes a rotation of gear 226 and a pinion 221 (Fig. 11) meshed therewith and rotatable on shaft 60. Pinion 221 has beveled teeth 222 secured thereon and meshed with cooperating beveled teeth on a smaller pinion 223. This small pinion 223 is pivoted on a stud 224 secured to a sleeve 225 surrounding shaft 60. Another pinion 226 is loosely mounted on sleeve 225 and meshes with a segment 227 secured to a sleeve 228 having a tongue connection with a drum 229. The drum 229 is connected by a link 230 with the kind of operation lever 141 shown in Fig. 1. Since this lever 141 remains in its position shown during all the operations described herein, the drum 229, sleeve 228, segment 227, and pinion 226 remain stationary at all times insofar as the description of the following operations is concerned.

Reverting now to the movement imparted to the pinion 221 by depression of one of the blind keys 20 or 22, it is seen that rotation of the pinion 221 causes rotation of the small pinion 223 and sleeve 225 in the same direction. This causes a corresponding rotation of a pinion 231 secured to the opposite end of the sleeve 225 and to a helical cam drum 232 having teeth meshing with pinion 231. Rotation of this drum 232 causes a roller 233 lying within its groove to be shifted laterally. This roller is connected to an arm 234 secured to shaft 140, so that rotation of the drum 232 by movement of the above described parts shifts the shaft laterally. Shaft 140 is secured to a frame plate 235 carrying shafts 130 and 134, the lateral movement of which selects the adding or subtracting side of the balance totalizer as clearly shown in Fig. 7.

From the above it is seen that depression of the deposit, positive new balance, or positive old balance keys, followed by depression of the key stem 24, causes the balance totalizer to be conditioned for adding, whereas depression of the withdrawal, negative new balance, or negative old balance keys, followed by depression of the key stem 24, causes the balance totalizer to be conditioned for subtracting.

Totalizer engaging and disengaging mechanism

The means of engaging and disengaging the totalizers shown in Fig. 2 involves mechanism to move the totalizer wheels toward the central shaft 146 by swinging the wheels about shafts 236 or 254 as a pivot. This mechanism includes a cam 304 (Fig. 9) secured to shaft 34 and cooperating with rollers 302 and 303 on an arm 301 secured to shaft 236. This shaft 236 is secured to the totalizer frame so that upon rotation of cam 304 the arm 301 and totalizer frame will oscillate about shaft 236 as a pivot. A side view of these parts is substantially the same as the showing of parts 251 to 254 (Fig. 3). This oscillation of the totalizer frame causes the actuating gears 50 (Figs. 2 and 3) to be engaged with intermediate gears 237 that are rotated differentially through gears 238 by the large differential gear 157 under control of a depressed amount key. During adding operations totalizers

are engaged for actuation just before the differential mechanism returns home from its moved position, and are disengaged at the end of such return movement, while for total taking a selected totalizer line is engaged at the beginning of a machine operation and is disengaged after the differentials have been actuated to their moved positions. For sub-totalizing the totalizers are engaged at the beginning of the operation and are left engaged until near the end of the operation, as is customary, and for non-adding operations they remain disengaged during the entire operation. The mechanism for controlling the timing of these four different types of operation does not form a part of the present invention and is therefore not shown.

It might be here mentioned that one engaging mechanism is provided for the adding inter-spersed totalizers in rows I, II, and III and a separate engaging mechanism is provided for the balance totalizer. By such provision it is possible to have the balance totalizer engaged while the other totalizers are disengaged and vice versa for the purpose of transferring totals.

Conditioning the machine for a balance operation

When it is desired to take a balance (taking a total from the balance totalizer) it is necessary only to move the balance lever 149 from its add to its balance position. This completely conditions the machine for a balance operation and releases the motor clutch and closes the motor switch to start the operation. During the lowering of this lever three separate functions are performed one after the other. The first is that of depressing one of the blind keys in the transaction blank for the purpose of selecting the proper transaction totalizer into which the balance will be transferred and for shifting the slide 16 (Fig. 12) to couple the proper blind key 20 or 22 for depression to properly shift the balance totalizer. It will be remembered that the selection of the blind key in the transaction bank and the consequent selection of the blind key 20 or 22 is under control of the overdraft mechanism above explained.

The initial downward movement of lever 149 raises link 269, rotating lever 261 counter-clockwise about its pivot 187 and lowering link 262. Link 262 at its lower end is pivoted to a short arm 263 secured to shaft 264 having also secured thereto another short arm 265 in turn pivoted to link 93a. The lowering of link 262 therefore lowers link 93a as well as an arm 266 pivoted at the upper end of link 93a and journaled on shaft 27. Lowering the arm 266 causes clockwise movement of bell crank 94 about its pivot 95, due to the pin and slot connection between the bell crank and arm 266. This clockwise movement depresses the selected one of the blind keys and adjusts the detent 10 to its upper or lower position as heretofore explained.

The initial movement of lever 149 also adjusts the timing mechanism for engaging the balance totalizer, so that it will be engaged and disengaged at the proper times for total taking. As above explained, this timing mechanism does not form a part of the present invention and is therefore not shown.

Continued movement of the balance lever 149 causes the upper end thereof to contact and move roller 257 (Fig. 12) mounted on an arm 268 secured to a short shaft 269. This movement rotates shaft 269 counter-clockwise as well as a short arm 270 also secured thereto. The arm 270

lies over the pin 271 secured on the inner end of the key stem 24 and thereby pulls the key stem into its depressed position. As above explained, this movement of the key stem shifts the balance totalizer under control of the overdraft mechanism.

As the balance lever is given its last increment of movement, a stud 272 secured on an ear on the lower end of the lever contacts and moves a release pawl 273 pivoted on a stud 274. This movement releases a clutch disc 275 to the action of a spring 276 to engage the drive shaft of the machine with the motor and to raise a switch lever 277 to close the electric circuit. Since the details of the motor clutch and switch mechanisms are well known in the art, no further detail thereof is given.

The balance lever 149 may be returned to its add position near the end of the operation by any suitable mechanism. An example of such mechanism is disclosed in the United States Patent 1,736,067 issued to Samuel Brand on November 19, 1929. However, since the specific form of return mechanism is not essential to an understanding of the present invention, it has not been shown.

Machine release for adding operations

During item entering operations involving the depression of transaction keys it is necessary only to press the proper amount keys together with the appropriate totalizer key 151 and the appropriate transaction totalizer key. The depression of the transaction totalizer key releases the clutch in a manner similar to that just explained in reference to the lowering of lever 149, so that there is no necessity for depressing a special motor bar. The details of this release mechanism, however, do not form a part of the present invention, so they are not shown.

During such operations it is, of course, necessary to depress the key stem 24 to select the plus or minus side of the balance totalizer, so special means has been provided to perform this function. Referring to Fig. 12, a disc 278 is secured to shaft 27 and has a shoulder 279 resting against a roller 280 on the lower end of an arm 281 secured to shaft 269. This shaft 27 receives one clockwise revolution each operation of the machine and therefore depresses key stem 24 at the beginning of such operation. The disc 278 is cut away at 282 to prevent interference of roller 280 with the periphery of the disc when the balance lever 149 is operated.

What I do claim is:

1. In a machine having an add and subtract totalizer, actuators for said totalizer, two depressible key stems, means controlled by the depressible key stems to selectively couple the totalizer with the actuators for taking a balance from the totalizer, a third depressible key stem, means operated by the depression of the third key stem to depress one or another of the said two key stems, and a balance lever movable into a balance position to condition certain elements of the machine for automatically taking a balance from said totalizer, the combination of means extending into the path of the balance lever and actuated by the balance lever as the balance lever is moved into its balance position, and an element integral with the last-named means coacting with the third key stem to depress the third key stem to thereby depress the said one or another of the said two depressible key stems upon movement of the balance lever into its balance position so that the totalizer is coupled

with the actuators prior to a machine operation.

2. In a machine having an add and subtract totalizer, actuators for said totalizer, means to selectively control engagement of the totalizer with the actuators, said means including a shiftable detent, means coacting with the detent to shift the detent into one position for adding operations and the taking of positive balances, means to shift the detent into another position for subtracting operations and the taking of negative balances, a depressible key stem, coupling elements settable to selectively couple the depressible key stem to one or the other of said two last-named means, machine driving means, and a balance lever to condition certain elements of the machine for taking a balance from said totalizer, the combination of a cam on the machine driving means; means actuated by the cam during adding and subtracting operations to depress the key stem to automatically shift the detent during the machine operation when adding or subtracting; and an extension integral with the last-named means located in the path of movement of the balance lever and actuated by the balance lever as the balance lever is moved into its balance position prior to a machine operation to shift the detent prior to a machine operation when preparing the machine for taking a balance from the totalizer.

3. In a machine having an add and subtract totalizer, said totalizer having an add side and a subtract side; classification totalizers, one associated with each side of the add and subtract totalizer; actuators for all of said totalizers; means to select the add or subtract side of the add and subtract totalizer for data-entering operations and for balancing operations; control keys to control the selection of the classification totalizers to receive entries during a balance operation; settable means adjusted under control of the control keys to determine which side of the add and subtract totalizer is to be selected; a balance lever movable from an add position into a balance position to condition certain elements of the machine for taking a balance from the add and subtract totalizer; means to actuate the classification totalizer selecting control keys; and mechanism connected with the balance lever and operated by the balance lever to operate said control key actuating means as the balance lever is moved toward its balance position to operate a control key and, through the operated control key, to simultaneously adjust the settable means to select the side of the add and subtract totalizer associated with the selected classification totalizer; the combination of means including an element having a projection extending into the path of movement of the balance lever so as to be actuated by the balance lever as the lever is moved into its balance position whereby the last-named means is actuated to operate the means to select the add or subtract side of the add and subtract totalizer after the balance lever through said mechanism has adjusted the settable means in accordance with a selected classification totalizer.

4. In a machine having an add and subtract totalizer, said totalizer having an add side and a subtract side; classification totalizers, one associated with each side of the add and subtract totalizer; actuators for all of said totalizers; means to select the add or subtract side of the add and subtract totalizer for data-entering operations and for balancing operations; control

75 keys to control the selection of the classification totalizers to receive entries during a balance operation; settable means adjusted under control of the control keys to determine which side of the add and subtract totalizer is to be selected; a balance lever movable from an add position into a balance position to condition certain elements of the machine for taking a balance from the add and subtract totalizer; means to actuate the classification totalizer selecting control keys; and mechanism connected with the balance lever and operated by the balance lever to operate said control key actuating means as the balance lever is moved toward its balance position to operate a control key and through the operated control key to simultaneously adjust the settable means to select the side of the add and subtract totalizer associated with the selected classification totalizer; the combination of 10 a device to operate the means to select the add or subtract side of the add and subtract totalizer; and an extension integral with the device projecting into the path of movement of the balance lever, said extension located at a distance from 15 the balance lever when the balance lever is in its add position so that the balance lever when moved toward its balance position engages the extension and operates the device after the said mechanism has adjusted the setting means.

5. In a machine having mechanism operable to perform data entry and balance withdrawing operations, a plurality of depressible control keys, a balance lever movable from a normal position to a balance position to condition said mechanism for balance withdrawing operations, connections between said lever and certain of said keys to depress a selected one of said certain keys, selecting means to select other of said keys for depression, and connections between 35 the said certain keys and said selecting means to determine which one of said other keys is to be depressed, the combination of devices to depress the selected one of the said other keys, and a member to operate said devices, said member having a portion thereof extending into the path 40 of movement of the balance lever, said portion being located from the normal position of the balance lever at sufficient distance that the balance lever operates the member and the devices 45 after the balance lever depresses the selected one of said certain keys and through the connection between said certain keys and said selecting means determines which one of the said other keys is to be depressed by the balance lever, 50 the depression of said selected keys being effected sequentially upon a single manipulation of the balance lever.

6. In a machine of the class described having a depressible key, and a manipulative lever movable to one position to condition the machine for item entry operations and movable into another position to condition the machine for balance withdrawing operations, in combination with means to depress said key, said means having a portion extending into the path of travel of the lever to be operated by the lever when the lever is moved to condition the machine for balance withdrawing operations to cause said means to depress the key; a power shaft operated during each machine operation; and an element on the power shaft to engage and operate said means during machine operations during which the lever is in its item entry position.

7. In a machine having an add and subtract

totalizer having an add side and a subtract side; transaction totalizers; actuators for said totalizers; means to couple the totalizers with the actuators; selecting means to select the add or subtract side of the first-named totalizer to shift the selecting means into position to select the add or subtract side of the add and subtract totalizer for coupling the selected side of the totalizer with the actuators for actuation, said means including a key stem; means to select one of the other totalizers for actuation, said means including key stems; a balance lever movable from a normal position into a balance position to condition the machine for withdrawing a balance from the add and subtract totalizer; and means operated by the lever as the lever is initially moved toward its balance position to depress one of the second-mentioned key stems; the combination of means having a portion extending into the path of the balance lever and operated by the lever upon further movement of the lever into its balance position to depress the first-mentioned key stem.

8. In a machine having a balance lever for controlling the machine for balancing operations and a machine release mechanism oper-

ated by the balance lever to release the machine for operation as the lever is moved into balance position; a plurality of classification totalizers; an add and subtract totalizer; means to select one of the classification totalizers for actuation; means to select the add or subtract side of the add and subtract totalizer; connections between the balance lever and the first-named selecting means to actuate the selecting means to select a classification totalizer; and means coacting with the first-named selecting means and the second-named selecting means and adjusted by the former when the former is actuated by the balance lever to adjust the second-named selecting means in a position corresponding to the classification totalizer selected; the combination of means connected to the second-named selecting means and engaged by the balance lever as the balance lever is moved to control the machine for balance operations to actuate the second-named selecting means to select the add or subtract side of the totalizer as determined by the selection of a classification totalizer by the first-named selecting means.
